UNITED STATES PATENT OFFICE.

WILLIAM J. BEST, OF DETROIT, MICHIGAN.

HYDROCARBON-BURNER.

1,299,108.

Specification of Letters Patent.

Patented Apr. 1, 1919.

Application filed June 22, 1918. Serial No. 241,407.

To all whom it may concern:

Be it known that I, WILLIAM J. BEST, a citizen of the United States, and residing at Detroit, in the county of Wayne and State 5 of Michigan, have invented a new and Improved Hydrocarbon-Burner, of which the following is a specification.

This invention relates to burners for alcohol and the heavier liquid hydro-carbons 10 such as kerosene, and its object is to provide a burner which will operate with a minimum of odor and produce a maximum of heat for the amount of fuel consumed.

This invention consists in the details of 15 construction shown in the accompanying drawing and particularly pointed out in the claims.

The burner is shown to be made up of an inner chimney, an outer chimney, a vaporizer 20 and a cowl. The inner chimney 1, is preferably cylindrical and provided with an imperforate top 2, a diaphragm 3 and with a centering ring 4 at its lower end to position it on the vaporizer. The inner chimney 25 and diaphragm are perforated to permit air to pass freely. The outer chimney 5 rests upon a shelf 6 formed on the upper edge of the outer side 7 of the vaporizer and the centering ring 4 rests on the upper edge of the 30 inner side 8. The width of the bottom 9 of the vaporizer is preferably sufficient to permit the wick 10 resting on this bottom to be substantially below the bead or rib 12 formed on the ring 4. The two sides 7 and 35 8 are perforated and are integral with the bottom. A fuel pipe 13 connects into this vaporizer and the cowl 14 may be supported by the crossed rods 15 extending through the chimneys.

40 When the burner is to be used, fuel is permitted to flow into the bottom of the vaporizer and a small wad of asbestos on the end of a wire is lowered down between the chimneys and dipped into the fuel, after which it 45 is lifted out, ignited, and again lowered to ignite the wick 10. Because of the bead 12, the wire will not engage the wick and injure it. The resulting flame will receive air through the holes in the sides 7 and 8, and as 50 these are integral with the bottom 9, the entire vaporizer soon becomes very hot, and the fuel becomes vaporized and burns between the sides of the vaporizer and between the chimneys, sufficient air entering through 55 the holes in the sides of the vaporizer and in

the chimneys to produce complete combustion and therefore a clear blue flame.

It has been found that the small amount of paraffin which is carried by most of the kerosenes on the American market is deposited in the bottom and against the lower part of the sides of the vaporizers now in the market. This deposit is very small on the inner side when such side is made integral with the inner chimney, as in my former Patent No. 1,177,297, dated March 28, 1916, but in that case, the paraffin is deposited at the lower edge of the outer side of the outer chimney. This coating acts like a wick in that it serves as a vehicle for the fuel which creeps up thereon or therein and evaporates on the upper surface thereof, producing a disagreeable odor. While a similar deposit occurs on the inner side of the outer chimney, the result is not so objectionable.

By forming the vaporizer with both sides and bottom integral; and both sides perforated so as to insure combustion between the sides, these sides get so hot that there is no deposit of paraffin where the sides of the vaporizer join the lower edges of the chimneys and there is therefore no escape of fuel vapor into the atmosphere at those points. The combustion of the fuel seems to be more perfect when highly heated in the vaporizer 85 and the odor of the burner is reduced to a minimum.

Sizes and proportions of this vaporizer may be changed within quite wide limits without departing from the spirit of my invention as set forth in the following claims.

I claim:—

1. A burner having concentric perforated outer and inner chimneys, a vaporizer integral with the lower ends of both outer and inner chimneys and in the form of a trough, and a fuel supply pipe connecting into the vaporizer.

2. A burner having concentric perforated outer and inner chimneys in sections, a vaporizer below the chimneys comprising a trough with which the lower sections of the chimneys are integral, and a fuel supply pipe connecting into the outer side of the vaporizer, the inner side of the vaporizer being 105 of less diameter than upper end of the inner chimney, a supporting ring mounted upon the upper edge of the lower section of the inner side to support the inner chimney, and a wick resting upon the bottom of the 110

vaporizer and fitting against the inner wall thereof.

3. A burner having perforated outer and inner chimneys in sections, a vaporizer below the chimneys and integral with the lower ends of both of them, a wick resting upon the bottom of the vaporizer, the inner

side of the vaporizer being of less diameter than the upper end of the inner chimney, and a support ring mounted upon the upper edge of the section of the inner chimney which is integral with the vaporizer to support the remainder of the inner chimney.

WILLIAM J. BEST.
